CLAIM

The ornamental design for display stand, as shown and described.

DESCRIPTION

FIG. 1 is a top plan view of my new design for a display stand;

FIG. 2 is a right side elevational view, the left side being a mirror image thereof;

FIG. 3 is a front end view thereof;

FIG. 4 is a rear end view thereof;

FIG. 5 is a top plan view of a second embodiment of that shown in FIG. 1;

FIG. 6 is a right side elevational view, the left side being a mirror image thereof;

FIG. 7 is a front end view thereof; and,

FIG. 8 is a rear end view thereof.

The broken line showing of a display card at the rear in FIGS. 2-4 and 6-8 is for illustrative purposes only.

FIG. 1.

FIG. 2.

FIG. 3.

FIG. 4.

FIG. 5.

FIG. 6.

FIG. 7.

FIG. 8.
